NOTEBOOK PAD

Harry L. Kalish, New York, N. Y.

Application December 30, 1935, Serial No. 56,692

5 Claims. (Cl. 281—29)

This invention relates to new and useful improvements in a note book pad.

The invention has for an object the construction of a note book pad which is characterized by 5 the provision of a plurality of sheets each with a line of perforations near the top dividing off a support area, and a cover secured near its top edge upon the front side of said support area and extending over the top and down the back and 10 up the front of said pad and arranged to have its free edge engageable beneath the said top edge for constituting the closed position of the pad.

Still further the invention proposes the provision of a transverse strip extended across the 15 support area of the pad and arranged in a manner so as to hold the top edge of the cover of the pad spaced from the front face of the pad in a manner so that the bottom edge of the cover may readily engage therebeneath.

Still further the invention also proposes an arrangement wherein staples may be used for the purpose of holding the transverse strip and the 20 sheets of the pad in a unit.

Still further the invention also contemplates an arrangement whereby the cover and the pad are 25 secured together along certain areas so that the cover is held upon the pad at the top thereof.

As another object of this invention it is proposed to provide an arrangement wherein the 30 cover is detachable from the pad in a particular manner, whereby refill pad sheets may be used on the same cover.

Still further the invention proposes a novel arrangement of a transverse sheet attached upon 35 the inner face of the top of the cover and associated with means by which the pad may be releasably held in position.

Still further the invention also proposes a novel arrangement of the upper edge of the cover in a 40 manner so that a portion thereof is bent under and secured upon the pad to form a bend which is disposed downwards under which the lower edge of the cover may be readily inserted.

Still further the invention proposes the construction of an article as mentioned which is 45 simple and durable and which may be manufactured and sold at a reasonable cost.

For further comprehension of the invention, and of the objects and advantages thereof, reference will be had to the following description and accompanying drawing, and to the appended 50 claims in which the various novel features of the invention are more particularly set forth.

In the accompanying drawing forming a material part of this disclosure:—

Fig. 1 is a perspective view of a note book pad constructed according to this invention and shown in a closed state.

Fig. 2 is a perspective view showing the pad of Fig. 1 in an open position.

Fig. 3 is an enlarged sectional view taken on the line 3—3 of Fig. 1.

Fig. 4 is a fragmentary sectional view taken on the line 4—4 of Fig. 3.

Fig. 5 is a fragmentary sectional view taken on the line 5—5 of Fig. 3.

Fig. 6 is a transverse sectional view similar to Fig. 3 but illustrating a modified form of the device.

Fig. 7 is a fragmentary sectional view taken on the line 7—7 of Fig. 6.

The note book pad according to this invention comprises a plurality of sheets 10 having lines of perforations 11 near the top thereof dividing off an area 12 by which the sheets may be supported 20 in pad formation. A spacer strip 13 is extended across the front side of the support area 12, and a staple 14 engages through the strip 13 and the support area of the pad for holding the sheets and the strip in a unit.

A cover 15 is associated 25 with the sheets in a novel manner and this cover comprises a top portion 15^a which is attached by glue 16 or the like upon the front side of the strip 13. The top portion 15^a continues into a portion 15^b which extends across the top of the 30 pad which in turn continues with a back portion 15^c extending along the back of the pad in turn connecting with a portion 15^d extending across the bottom of the pad and which is in turn connected with a front portion 15^e extending up 35 across the front of the pad. The free end of the portion 15^e engages beneath the front edge of the top portion 15^a and in this manner the cover is held in the closed position.

The parts are so proportioned that the bottom edge of the strip 13 40 is slightly above the edge of the portion 15^a to provide an area into which the free edge of the portion 15^e may engage. The junction between the portions 15^b and 15^c is secured upon the top edge of the pad by glue, cement or other material 17.

The lines of perforations 11 constitute an important feature of this invention in that then the leaves of the pad may be easily detached along these lines without disturbing the support area 12 and the relation of the cover upon this support 50 area.

A further feature of the invention is the arrangement of a cover in such a manner that it is constructed of one piece of material and in which the free edges of the portions 15^a and 15^e are 55

adapted to coact with each other for holding the cover in the closed position. In Fig. 2 the cover is shown in the open position so that the relation of the lines of perforations 11 to the strip 13 may be readily understood. The staple 14 is of a type having a pair of arms which are extended through the material of the support area 12 and the ends thereof bent outwards so as to anchor the staple in position.

10 In Figs. 6 and 7 another embodiment of the invention has been disclosed wherein provision is made for the disconnection of the pad from the cover so that the cover may be provided with refills after the pad is all used up. According to 15 this form of the invention the note book pad comprises a plurality of sheets 10 having lines of perforations 11 near the top thereof dividing off a support area 12 by which the sheets may be supported. A strip of material 13' is secured at its 20 edges 13^a upon the rear edges of the front portion 15^a of the cover. The device is provided with a cover 15 having the parts previously described with respect to the previous form, which parts may be recognized in that they are numbered 25 with the same reference numerals. A staple 14 is engaged through the support area 12 of the pad and comprises a front portion connecting with a pair of arms, and ends 14' of the arms being bent outwards at the back of the pad for 30 the purpose of holding the staple in position. The arrangement is such that the arms are slightly longer than the thickness of the support area so as to cause the front portion to stand away from the front of the pad to accommodate a support 35 strip 13' as hereinafter further described.

The support strip 13' is formed with a pair of slots 13^b extended in from the bottom edge and an eyelet 20 is rotatively mounted upon the inner end of each of the slots 13^b. Each of the eyelets 40 20 have projections 20' by which they may be rotated at desired. Each of the eyelets 20 is formed with a radial slot 20^a adapted to align with the slot 13^b in one position of rotation of the eyelet for the purpose of allowing passage of 45 the arms of the staple 14.

In Fig. 7 the eyelets 20 are shown in a position in which the pad is firmly attached upon the support strip 13'. If it is desired to disconnect the pad from the cover the projections 20' should be 50 turned to positions in which the slots 20^a align with the slots 13^b. Then the cover and support strip may be moved relatively to the pad so that the arms of the staple disengage through the slots 13^b.

55 The pads 10 are provided with adhesive material 17 upon the upper back edges thereof. This adhesive 17 is of a type adapted to be wetted for it to become operative. It is proposed that when a refill pad is engaged within the cover the adhesive 17' is wetted and in this manner attached to the junction between the sides 15^b and 15^c of the cover. Fig. 6 shows the note book pad in operative position. After the leaves of the pad have been exhausted the pad may be removed by 60 first tearing loose the adhesive 17' from the support area of the pad and then the projections 20' of the eyelets are exposed so as to be movable as before described to allow the disconnection of the staple from the support strip 13'.

70 While I have shown and described the preferred embodiment of my invention, it is to be understood that I do not limit myself to the precise construction herein disclosed and the right 75 is reserved to all changes and modifications com-

ing within the scope of the invention as defined in the appended claims.

Having thus described my invention, what I claim as new, and desire to secure by United States Letters Patent is:—

5 1. A note book pad, comprising a plurality of sheets having lines of perforations near the top dividing off support areas, and a cover for the pad having a top portion secured upon the front side of said support area, and continuing across the 10 top of the pad down the back of the pad across the bottom of the pad and up the front of the pad terminating in an edge adapted to engage beneath the edge of the top portion for holding the cover in the closed position, and a spacer strip 15 attached upon the front of the support area for the purpose of holding the front portion of the cover slightly spaced so that the edge of the bottom portion may be engaged therebeneath.

2. A note book pad, comprising a plurality of 20 sheets having lines of perforations near the top dividing off support areas, and a cover for the pad having a top portion secured upon the front side of said support area, and continuing across the top of the pad down the back of the pad across 25 the bottom of the pad and up the front of the pad terminating in an edge adapted to engage beneath the edge of the top portion for holding the cover in the closed position, and a spacer strip 30 attached upon the front of the support area for the purpose of holding the front portion of the cover slightly spaced so that the edge of the bottom portion may be engaged therebeneath, the bottom area of the spacer strip being arranged slightly above the free edge of the top 35 portion of the cover to provide an area into which the edge of the bottom portion of the cover may engage.

3. A note book pad, comprising a plurality of 40 sheets having lines of perforations near the top dividing off support areas, and a cover for the pad having a top portion secured upon the front side of said support area, and continuing across the top of the pad down the back of the pad across 45 the bottom of the pad and up the front of the pad terminating in an edge adapted to engage beneath the edge of the top portion for holding the cover in the closed position, and a spacer strip 50 attached upon the front of the support area for the purpose of holding the front portion of the cover slightly spaced so that the edge of the bottom portion may be engaged therebeneath, the bottom area of the spacer strip being arranged slightly above the free edge of the top 55 portion of the cover to provide an area into which the edge of the bottom portion of the cover may engage, and the rear face of the top portion of the cover being adhesively connected with the front face of said spacer strip.

4. A note book pad, comprising a plurality of 60 sheets having lines of perforations near the top dividing off support areas, and a cover for the pad having a top portion secured upon the front side of said support area and continuing across the top of the pad down the back of the pad 65 across the bottom of the pad and up the front of the pad terminating in an edge adapted to engage beneath the edge of the top portion for holding the cover in the closed position, and a spacer strip 70 attached upon the front of the support area for the purpose of holding the front portion of the cover slightly spaced so that the edge of the bottom portion may be engaged therebeneath, the bottom area of the spacer strip being arranged slightly above the free edge of the top 75 portion of the cover.

portion of the cover to provide an area into which the edge of the bottom portion of the cover may engage, and the rear face of the top portion of the cover being adhesively connected with 5 the front face of said spacer strip, and the upper corner of the back of the support area being adhesively connected with the junction of the top of the back portions of said cover.

5. A note book pad, comprising a plurality of 10 sheets having lines of perforations near the top dividing off support areas, and a cover for the pad having a top portion secured upon the front side of said support area, and continuing across the top of the pad down the back of the pad 15 across the bottom of the pad and up the front of the pad terminating in an edge adapted to engage

beneath the edge of the top portion for holding the cover in the closed position, and a spacer strip attached upon the front of the support area for the purpose of holding the front portion of the cover slightly spaced so that the edge of the bottom portion may be engaged therebeneath, the bottom area of the spacer strip being arranged slightly above the free edge of the top portion of the cover to provide an area into which the edge of the bottom portion of the cover may engage, and the rear face of the top portion of the cover being adhesively connected with the front face of said spacer strip, and a staple engaging through the spacer strip and the support area of the cover for holding these parts in a unit. 10 15
